UNITED STATES PATENT OFFICE.

FERNANDO J. LE BEAU, OF CHICAGO, ILLINOIS, ASSIGNOR OF ONE-HALF TO FREDERICK LUNDIN, OF CHICAGO, ILLINOIS.

EMERGENCY LIFT-LATCH.

1,252,454.

Specification of Letters Patent.

Patented Jan. 8, 1918.

Application filed March 7, 1917. Serial No. 152,983.

To all whom it may concern:

Be it known that I, FERNANDO J. LE BEAU, a citizen of the United States, residing at Chicago, in the county of Cook and State of Illinois, have invented a certain new and useful Improvement in Emergency Lift-Latches, of which the following is a specification.

This invention relates to latches or catches applicable to the lower portion of a door to, in proper position, engage the floor itself or a member placed thereon to secure the door in locked position. The object of the invention is to provide means through which such a latch is prevented from extending below the surface of the lower edge of the door with possible injury to the floor over which the door swings, except when the door is in closed or locked position, in which position the latch device is located in normal operative position below the edge of the door. The device is especially useful in cases where no threshold plate is used under a door.

This invention consists broadly in mounting the entire latch upon a carriage slidable vertically with reference to the door, in combination with automatic means by which the carriage is retained in such a position that the latch device locks the door when the door is closed, while in all other positions the latch mechanism is automatically lifted bodily to a point where the latch cannot possibly injure the floor over which the door swings. The invention is especially valuable in the case of emergency fire exit doors swinging over fine Mosaic floors which would be seriously damaged by a sharp pointed latch dragging over the floor.

The invention further consists in the features and details of construction which will be hereafter more fully set forth in the specification and claims.

Referring to the drawings, in which similar numerals indicate the same parts throughout the several views,

Figure 1 illustrates an emergency exit door of the general type shown in United States patent to E. A. Freed, Number 992,554, dated May 16th, 1911, having a form of the device of this invention specially adapted for use therewith applied thereto, the front or movable plate of the door being removed, and the parts being in

the position which they assume when the door is unlatched either open or opening.

Fig. 2 is a changed position view, corresponding to Fig. 1, showing the door closed and locked or latched.

Fig. 3 is a side view of the latch mechanism taken on the line 3 of Figs. 1 and 4.

Fig. 4 is a detailed view taken on the line 4 of Fig. 5.

Fig. 5 is a side view of the door with the latch mechanism in the position assumed in Fig. 1, the same being taken on the line 5 of that figure.

Fig. 6 is a changed position view of the parts shown in Fig. 5, taken on the line 6, of Fig. 2.

The device of this invention is applicable to almost any sort of a door, but because it is especially applicable to emergency exit doors, it is shown in the drawings applied inside of a door of the type of the Freed patent, heretofore referred to.

The body of the door comprises a rear wall 10 inclosed by side and bottom flanges 12, 13 and 14, the latter terminating in a relatively narrow inwardly pointed face 80 flange 16, parallel to back 10, all as shown in the drawings. Loosely mounted inside this body just described, adapted for movement toward and from the rear wall 10 and retained against outward movement by the 85 flange 16, is the front plate 18, spring pressed outward by any suitable sort of spring devices, as for instance the springs 20, inclosing telescoping bolts 21 and 22. As in the Freed patent, the door is so mounted that the plate 10 faces the room from which emergency exit is to be effected so that a person in the room can, by pressing upon any part of the plate 18, manipulate the latch mechanism of the door and permit 95 the door to open.

The particular form of latch mechanism with which this invention is concerned is, for purposes of convenience, mounted upon a relatively small back plate 26 rigidly connected by any suitable means, as for instance through holes 28, to the lower outer swinging corner of door plate 10. Extending forward from this back plate 26 are two parallel U-shaped supports 30 spaced apart 105 as shown for the reception between them of a carriage 34 mounted upon rods 36 and 38, extending through supports 30 so as to slide

vertically thereon with reference to the door. In the particular case here illustrated, the rod 36 is secured rigid with reference to lugs 40 on the adjacent side of the carriage 34 by cotter pins 42, while rod 38 is secured rigid on its adjacent support 30 by any suitable means, as for instance by pins 44, but this difference in fastening the rods is not in any way material. The rod 38 is, as 10 clearly shown in Figs. 1 and 2, made to extend substantially above the adjacent support 30, and is provided with a coiled spring 46 bearing against a stationary collar 48 on the opposite end of the rod 38, and against 15 the flange 40 on the carriage so that this spring can move the carriage 34 downward; thus, in the absence of other mechanism, driving the latch dog 50, supported by the carriage, into the recess 52 in the floor 54 and door sill 56 over which the door swings.

This latch dog 50 is pivoted at 58 between opposite side walls of the carriage 34 and is adapted to swing between the position shown in full lines and a position slightly 25 beyond the dotted line position of Fig. 6, and vice versa. This latch dog 50 is retained in the full line position by a locking plate 60 pivoted at 62 and pressed outward to the full line position of Fig. 6 by spring 30 64 placed inside the carriage 34, as shown, the outer end of the spring being housed inside of a lug or knob 66 of such a size, shape and position that it is engageable by the front pressure plate 18 of the door so that 35 pressure on the door will move this knob 66 from the full line position of Fig. 6 to and beyond the dotted line position of that figure, to release the latch 50 and thus unlock the door. The details of the carriage, latch, and 40 locking plate are all the subject-matter of the specification and claims of my companion application filed herewith, Serial Number 152,982.

When the latch dog 56 is held rigidly in 45 place in the full line position of Fig. 6, the carriage 34 with latch dog 50 attached is essentially a rigid plunger bolt or locking latch slideable with reference to the supports 30. This rigid plunger bolt is normally held 50 in the raised position of Figs. 1, 4 and 5 by a lever mechanism comprising a link 70 pivoted at one end at 72 to the lower side of the carriage 34, and pivotally connected at its other end at 74 to a lever 76 pivoted to 55 plate 26 at 78, there being rigidly extending from this lever 76 an arm 80, controlled by a retractile spring 82 attached to the plate 26 at 84. The spring 82 is stronger than the spring 46, heretofore described, so that normally the parts are held by the spring 82 60 in the position of the figures last named. Link 70 is provided with an elongated slot 79 for pivot pin 74, thus allowing reciprocation of the bolt mechanism proper upward 65 against the action of spring 46 during the

time the parts are in the position of Fig. 2 or, more particularly, as the parts are approaching that position in the act of closing the door.

Pivoted at the proper point on the arm 70 80 is a rod 86 extending across the interior of the door through a suitably arranged perforation 88 in the edge 14 of the door. This rod 86 is made of sufficient length so that its end 90 projects outside the door whenever 75 the parts are in the position of Figs. 1, 4 and 5.

When, now the operator closes the door, the end of the rod 90 bears against the edge 80 of the door casing with the result that as the door closes, all of the parts move from the position of Fig. 1 to that of Fig. 2, wherein the carriage 34 is depressed and the latch 50 enters locking recess 52 and thus secures the door as shown.

Suppose now the parts are in the position of Figs. 2 to 6 and that a person on the inside of the room controlled by the door presses upon plate 18. The pressure on this plate 18 causes the plate to move inward and thus move locking member 60 from its full line position of Fig. 6 toward the dotted line position of that figure. A slight movement of this plate 60 releases latch 50 whereupon the latch begins to swing 95 upward toward the dotted line position of Fig. 6 and the whole door begins to swing from the full line to the dotted line position of that figure, and thence on beyond the dotted line position until finally 100 the latch member 50 entirely clears the door sill 56 and the door is in the act of swinging to fully open position, but the act of starting to open the door also releases the end 90 of rod 86 in the door frame 105 92, with the result that spring 82 acts to raise the carriage and the latch from the position of Fig. 2 to that of Fig. 1. In practice, the raising motion of the spring 82 combines with the motions described in 110 connection with Fig. 6 so that by the time latch 50 has passed off from door sill 56, it is safely elevated above the floor 54 if not actually in the position of Fig. 1, with the result that there is no possibility of the 115 sharp edge of the latch 50 engaging and scratching or tearing the floor, whatever its fine construction may be, as the door swings open.

Obviously, the operations described are 120 reversed as the door is moved from fully open to finally closed position.

Having thus described my invention, what I claim as new and desire to secure by Letters Patent is:

1. In a device of the class described, in combination with a door and its frame, a bolt adapted to pass below the edge of the door into the floor to lock it, a carriage for the bolt mechanism bodily reciprocatable to 130

and from the bottom of the door, means mounting the bolt for reciprocation in said carriage, mechanism normally holding the carriage with bolt mechanism attached in 5 such a position that the bolt entirely clears the floor in all positions of the door, and mechanism operatable only as the door approaches closed position automatically depressing the carriage with bolt attached to 10 the position wherein the bolt is in normal position for locking the door.

2. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all positions of the door, and mechanism engaging the carriage elevating mechanism adapted to engage the frame of the door as the door approaches closed position to move the carriage so that 20 the bolt is in normal position for locking the door to the floor during the time that the door is closed.

3. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all positions of the door, and a rod engaging the carriage elevating mechanism adapted to engage the frame of the door as the door approaches closed position to move the carriage so that the bolt is in normal position for locking the door to the floor during the time that the door is closed.

4. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all positions of the door, mechanism operatable only as the door approaches closed position 55 automatically depressing the carriage with bolt attached to the position wherein the bolt is in normal position for locking the door, and a flexible connection between the carriage elevating mechanism and the carriage permitting independent reciprocation of the carriage and bolt.

5. In a device of the class described, in combination with a door and its frame, a bolt adapted to pass below the edge of the door into the floor to lock it, a carriage for

the bolt mechanism reciprocatable to and from the bottom of the door, mechanism normally holding the carriage with bolt mechanism attached in such a position that the bolt entirely clears the floor in all positions of the door, mechanism engaging the carriage elevating mechanism adapted to engage the frame of the door as the door approaches closed position to move the carriage so that the bolt is in normal position 70 for locking the door to the floor during the time that the door is closed, and a flexible connection between the carriage elevating mechanism and the carriage permitting independent reciprocation of the carriage and 75 bolt.

6. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all positions of the door, a rod engaging the carriage elevating mechanism adapted to engage the frame of the door as the door approaches closed position to move the carriage so that the bolt is in normal position for 85 locking the door to the floor during the time that the door is closed, and a flexible connection between the carriage elevating mechanism and the carriage permitting independent reciprocation of the carriage and 90 bolt.

7. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all positions of the door, mechanism operatable only as the door approaches closed position automatically depressing the carriage with bolt attached to the position wherein the bolt is in normal position for locking the door, a 105 flexible connection between the carriage elevating mechanism and the carriage permitting independent reciprocation of the carriage and bolt, and spring means tending to so move the carriage mechanism outward 110 from the door.

8. In a device of the class described, in combination with a door and its frame, a bolt adapted to pass below the edge of the door into the floor to lock it, a carriage for the bolt mechanism reciprocatable to and from the bottom of the door, mechanism normally holding the carriage with bolt mechanism attached in such a position that the bolt entirely clears the floor in all posi- 125

tions of the door, mechanism engaging the carriage elevating mechanism adapted to engage the frame of the door as the door approaches closed position to move the carriage so that the bolt is in normal position for locking the door to the floor during the time that the door is closed, a flexible connection between the carriage elevating mechanism and the carriage permitting independent reciprocation of the carriage and bolt, and spring means tending to so move the carriage mechanism outward from the door.

9. In a device of the class described, in combination with a door and its frame, a bolt adapted to pass below the edge of the door into the floor to lock it, a carriage for the bolt mechanism reciprocable to and from the bottom of the door, mechanism normally holding the carriage with bolt mechanism attached in such a position that the bolt entirely clears the floor in all positions of the door, a rod engaging the carriage elevating mechanism adapted to engage the frame of the door as the door approaches closed position to move the carriage so that the bolt is in normal position for locking the door to the floor during the time that the door is closed, a flexible connection between the carriage elevating mechanism and the carriage permitting independent reciprocation of the carriage and bolt, and spring means tending to so move the carriage mechanism outward from the door.

10. In a device of the class described, in combination with a swinging door, a reciprocatable bolt near one edge thereof normally engaging the floor to lock the door, a carriage for the bolt and its mechanism reciprocable to move on the door from a position in which the bolt is in locking engagement with the floor to a position where the bolt entirely clears the floor under all conditions of movement of the bolt and door, a lever mechanism mounted on the door and connected to the bolt carriage for producing reciprocatory movement of the bolt carriage, a spring engaging said lever mechanism adapted to hold the carriage in elevated position, and a rod connected at one end to the lever mechanism having its other end adapted for engagement with the edge of the door frame when the door is closed, and to clear it at other times, the parts being so proportioned that the act of closing the door causes said lever mechanism to move con-

trary to its controlling spring to depress the carriage until the bolt is in the normal position for locking the door.

11. In a device of the class described, the combination with a door and a door frame, a reciprocatable plunger bolt carried by the door and movable into engagement with the door frame, a pivoted latch on the end of the plunger bolt engaging the door frame, releasable means for holding the pivoted latch normally rigid with reference to the bolt proper, and mechanism connected to the bolt normally holding the bolt retracted from the frame and operable by engaging a portion of the door frame remote from the bolt automatically forcing the bolt into engagement with the frame when the door closes.

12. In a device of the class described, the combination of a door member, a carriage slideable up and down toward the bottom thereof, means normally pressing the carriage toward said bottom, a latch member pivotally mounted on the carriage and normally projecting from the bottom of the door, means locking said last member in rigid position with reference to its pivot without interfering with the reciprocation of the carriage with latch attached, means operable by a person desiring to pass through the door for releasing the locking means which secures the latch member, mechanism adapted to bodily reciprocate said carriage with latch attached up and down with reference to the bottom of the door, spring mechanism, stronger than said first mentioned means, normally pressing said carriage toward the bottom of the door, adapted to hold the carriage and latch member in such a position that the latch member is substantially above the floor, mechanism operable only as the door is completely closed, moving said carriage downward against the action of the last mentioned spring mechanism so that the latch device engages the floor to lock the door, and means permitting independent reciprocation of the carriage under control of the first spring, for the purposes set forth.

In witness whereof, I have hereunto subscribed my name in the presence of two witnesses.

FERNANDO J. LE BEAU.
